UNITED STATES PATENT OFFICE.

JOHN WILSHUSEN, OF CHICAGO, ILLINOIS.

SOAP-HOLDER.

1,050,504.

Specification of Letters Patent. Patented Jan. 14, 1913.

Application filed March 8, 1911. Serial No. 613,118.

To all whom it may concern:

Be it known that I, JOHN WILSHUSEN, a citizen of the United States, and a resident of the city of Chicago, county of Cook, and 5 State of Illinois, have invented certain new and useful Improvements in Soap-Holders, of which the following is a specification.

My invention relates to improvements in soap holders and has for its object the production of a device of this character by 10 means of which a bar of soap may be mounted in convenient proximity to the wash basin and at the same time positively locked in position against surreptitious removal.

15 A further object is the production of the device of the character mentioned which will be of durable and economical construction and efficient in operation.

Other objects will appear hereinafter.

20 With these objects in view my invention consists in a soap holder characterized as above mentioned and in certain details of construction and arrangements of parts all as will be hereinafter more fully described 25 and particularly pointed out in the appended claim.

My invention will be more readily understood by reference to the accompanying drawing forming a part of this specification, and in which—

Figure 1, is a sectional side elevation of a soap holder embodying the invention, Fig. 2, is a transverse section taken on line $x-x$ of Fig. 1, and Fig. 3, is a transverse section 35 taken on line $y-y$ of Fig. 1, the soap being omitted.

The preferred form of construction as illustrated in the drawing comprises an elongated body comprising the supporting 40 or bracket forming portion 1, the rearward end 2 of which is flared or enlarged for rigid securing to a suitable supporting surface, screws 3 being used to effect said securing. The member 1 although illustrated 45 as being but a straight bar, may be bent or formed as desired to adapt the same to the construction of the wash basin upon which the device is to be used.

Arranged upon the outer end of the member 1 is the soap supporting arm or member 4 extending co-axial therewith, said members 1 and 4 being rigidly secured together through the medium of the pin 5. Arranged upon the member 4 is the soap bar 6, the 55 latter being tubular in form, the opening 7 therethrough being adapted to snugly re-

ceive the supporting member 4. The opening 7 and the member 4 are preferably of corresponding polygonal form in cross section, as clearly shown in Fig. 2, since with 60 said construction the soap bar will be locked against rotary movement. The supporting member 4 and a bar 6 are co-extensive in length. A flange 8 formed upon member 1 at the rearward extremity of the member 4 65 serves as a stop to prevent rearward longitudinal movement of the bar upon said supporting member. Longitudinal movement of said bar in the opposite direction, that is forwardly, is prevented by the circular stop 70 or head 9, which is arranged at the forward extremity of the member 4. A stem 10 formed centrally upon the member 9 fits loosely in the outer end of a socket 11 formed longitudinally in the member 4, the 75 stem 10 and the outer end portion of the socket 11 being preferably squared in order to prevent rotary movement of the member 9. Carried by the stem 10 is a spring arm 12, the rearward end 13 thereof which is 80 embedded in the stem 10 being bent at right angles to the body thereof, said stem 10 being correspondingly formed in order to establish a firm connection between said stem and said arm. The outer end 14 of the 85 member 12 is bent upwardly or hooked in form for engagement with an opening 15 provided in the member 4, preferably midway between the ends thereof, the inherent resiliency of said arm 12 normally maintaining the end 14 thereof in engagement with 90 said opening 15. With this arrangement, upon insertion of the arm 12 and the stem 10 of the stop 9 in to the socket 11, the end 14 of said spring arm will automatically engage the opening 15 to effect the locking of 95 the said stop in operative position, it being obvious that, when said stop is in operative position, removal of the soap bar is prevented.

In order to effect releasing of the spring or locking arm 12 a screw plug 16 is threaded into the opening 15. With this provision, upon desiring to release said spring arm, said plug needs only to be 105 threaded into the opening 15, since by so doing the end 15 of said spring arm will be lowered out of engagement with said opening; whereupon the stop 9 will be unlocked and free for removal. Said plug 16 will, 110 however, normally be positioned in the upper or outer end of the opening 15 in

order to permit of the end 15 of the spring arm engaging the lower or inner end of said opening.

In use, assuming the stop 9 to be removed from the supporting member 4 and the plug 16 to have been reversely rotated to position the same at the outer end of opening 15, a bar of soap may be readily and quickly slid to position upon said supporting member. Upon said soap bar being properly positioned upon the member 4, the outer end of the spring arm 12 and the stem 10 of the stop 9 are inserted into position in the socket 11, said stop being automatically locked in position by the spring arm 12 when said stop is in operative position. After said stop is so positioned and locked the soap bar will be locked in position thereby, removal thereof being prevented without mutilating the same. The soap bar when in position upon the member 4 prevents unlocking of the stop 9 since said bar, when positioned upon the member 4 covers the outer end of the screw plug 16. Hence, unlocking of said stop may be effected only upon exposure of the lateral surface of the member 4 which is only possible by wearing the soap away through usage thereof. When the soap bar has been worn to expose the lateral surface of the member 4 said screw 16 may be rotated through the medium of a screw driver or other tool designed for that purpose to effect the release of the stop 9 in which event a new bar may be slid to position.

A soap holder of the construction as set forth is of simple and economical construction, hence may be manufactured at a low cost. The same is adapted to support the bar of soap so that the same will be con-

venient for use. By reason of the bar being so supported the wash basin may be kept in a more tidy condition since the soap will not be brought in contact therewith. In addition, the unauthorized removal of soap is 45 positively prevented.

While I have illustrated and described the preferred form of construction for carrying my invention into effect, this is capable of variation and modification without departing from the spirit of the invention. I, therefore, do not wish to be limited to the exact details set forth, but desire to avail myself of such variations and modifications as come within the scope of the appended 50 55 claim.

Having described my invention what I claim as new, and desire to secure by Letters Patent is:

The combination with a soap bar, of a 60 tubular supporting bar having a threaded opening leading into the interior thereof; a threaded plug extending but part way into said opening so as to provide a recess in the inner portion of said opening, the outer end 65 of said plug being covered by the soap bar; a stop for the inner end of the soap bar; and a stop member carrying a spring arm extending into said supporting bar and having an angularly turned end adapted to engage in said opening to lock said stop member in position, substantially as described.

In testimony whereof I have signed my name to this specification in the presence of two subscribing witnesses.

JOHN WILSHUSEN.
